UNITED STATES PATENT OFFICE.

FREDERICK L. CUMMINGS, OF BOSTON, MASSACHUSETTS.

BOTTLE-CARRIER.

1,022,538.

Specification of Letters Patent.

Patented Apr. 9, 1912.

Application filed April 6, 1911. Serial No. 619,347.

To all whom it may concern:

Be it known that I, FREDERICK L. CUMMINGS, a citizen of the United States, and resident of Boston, in the county of Suffolk and State of Massachusetts, have invented an Improvement in Bottle-Carriers, of which the following description, in connection with the accompanying drawings, is a specification, like letters on the drawings representing like parts.

The present-day practice of retailers to furnish purchasers of merchandise with handle carriers therefor has created a demand for a type of carrier of simple construction which may be conveniently packaged in large numbers, and sufficiently inexpensive so that the cost thereof is not a serious item in the selling expense. My invention is designed to supply such a carrier especially adapted for bottles, such as milk bottles and the like, having these and other desirable attributes.

My improved carrier is preferably formed of a single piece of wire bent and looped in a novel manner so as to be self-adjusting to the necks of bottles of a considerable diversity of sizes, and, when adjusted to carrying position, to securely clamp a considerable part of the circumference of the bottle neck; the construction being such that the turning of the bail or handle part of the carrier around to carrying position securely clamps and locks the gripping portions to the bottle neck; the construction is further such that the carriers as formed ready for use lie flat so that they can be readily nested for packing.

The invention will be more fully understood from the following description, in connection with the accompanying drawings, and thereafter pointed out in the appended claims.

Referring to the drawings, Figure 1 is a front elevation of my improved carrier; Fig. 2 is a side view thereof; and Fig. 3 is a side view of the same as applied and adjusted to carrying position on a bottle.

A wire 10, of a size so as to be bendable without great effort yet of some considerable rigidity and elastic property, is formed with a bail or handle portion 11. From one side of the bail the wire extends angularly for some distance as at 12 to a sharp bend 13 extending thence in a circularly curved neck-clamping portion 14 and terminating in another sharp bend 15 forming

a hook 16. At the other side of the bail, the wire extends angularly in converging relation to the portion 12, as shown at 17, passing through the hook 16 to a circularly curved portion 18 coöperative with the portion 14 in clamping the bottle neck, and terminating in a sharp bend 19 constituting a hook 20 engageable with the bend 13 as clearly shown in Fig. 1. A hand grip 21, usually made of wood, may be fitted over the bail portion 11. As before stated, the wire is preferably formed of elastic stock, and the circularly curved portions 14 and 18 are bent so that the space normally enclosed thereby is as small or smaller than the sizes of bottle to be usually carried.

It will be observed that, by virtue of the capacity of the portion 17 to slide through the bend 15, the circularly curved portion 14 may be expanded within considerable limits to coöperate with the portion 18 in clamping bottle necks of a wide variety of sizes. Further, that after these portions 14 and 18 are snapped over the bottle neck, the bail 11 being turned up at right angles to the portions 14, 18, *i. e.* lengthwise of the bottle in position to carry the same as shown in Fig. 3, a rectangular bend is formed at 22 coöperative with the bend 15 to lock the portions 14, 18 in secure clamping engagement with the bottle neck. It is to be further observed that, in case it is desired to clamp a bottle neck smaller than the normal aperture between the circularly curved parts 14, 18, these may be inserted over the bottle neck and the side wire portion 17 drawn through the bend 15 until the portions 14, 18 tightly engage the bottle neck, when the bail may be turned up into locking-carrying position as described.

In the preferred form shown, the hand grip portion of the bail is made relatively wide to accommodate the hand and the side portions 12, 17 converge toward the neck clamping portions. This feature of construction is important and desirable not only in affording a wider hand grip but, particularly in the case of the converging portion 17, as this is slid through the bend 15 to enlarge the neck clamping aperture, the outward slant of the wire will insure its continued firm seating in the bottom of the bend 15, while after the handle portion is turned up vertically this bowed-out form prevents any casual disengagement which might result from a slipping of the handle

downward through its hook, were it extended straight up therefrom.

I thus produce a bottle carrier which can be made in wholesale quantities at a cost so insignificant as to be no serious item in the sales expenses; further, the carrier as supplied to the trade lies flat and virtually in one plane, so that it can be nested and boxed with the greatest facility.

- 10 I consider the construction whereby the neck-clamping portions are self-adjustable to locking position, and that whereby they are locked by a simple movement of the bail to carrying position, as of primary importance, and I desire to cover this construction broadly, as also the embodiment wherein a carrier having these attributes is formed from a single piece of wire stock bent as described.
- 20 Having described my invention, what I claim as new and desire to secure by Letters Patent is:
1. A bottle carrier, composed of wire bent to lie flatwise substantially in a plane with its end portions formed into a bottle neck clamping opening, the wire converging to the opening formed of such end portions from a relatively wide handle grip formed of the central portion of the wire.
  - 30 2. A bottle carrier, composed of wire

formed centrally as a relatively wide handle-grip and with intermediate portions converging to a bottle neck clamping opening formed of the end portions of the wire, the wire to form this opening having one end bent to embrace one side of a bottle neck and formed with a hook at its extremity, and the other end adapted to slide through said hook with a bend to embrace the other side of the bottle neck and its extremity formed with a hook to engage with a wire at the side of the bottle opposite said first hook, said bail and said two neck clamping portions lying in a common plane before application to the bottle, whereby the clamp opening may be adjusted by sliding the wire through the first named hook, and the clamping portions may be securely locked in clamping engagement with the bottle neck and against relative movement by bending the bail portions of said hooks at right angles to its initial position.

In testimony whereof, I have signed my name to this specification, in the presence of two subscribing witnesses.

FREDERICK L. CUMMINGS.
